UNITED STATES PATENT OFFICE

138,412

DESIGN FOR A BASE FOR MACHINE TOOLS OR THE LIKE

Robert Elvin Conover, Dayton, Ohio, assignor to
The Sheffield Corporation, Dayton, Ohio, a cor-
poration of Ohio

Application May 13, 1943, Serial No. 110,263

Term of patent 14 years

(Cl. D54—14)

To all whom it may concern:

Be it known that I, Robert Elvin Conover, a citizen of the United States of America, residing at Dayton, in the county of Montgomery, State of Ohio, have invented a new, original, and ornamental Design for a Base for Machine Tools or the like, of which the following is a specification, reference being had to the accompanying drawing, forming part thereof. In the drawing:

Fig. 1 is a front elevational view of a base for machine tools or the like showing my new design;

Fig. 2 is a side elevational view thereof; and,

Fig. 3 is a perspective view of the same, as viewed from the front and side.

The design comprises a base having a pair

of similar end sections of generally rectangular form with rounded corners, the end sections protruding forwardly from a central section. The central section has a front upwardly extending wall offset rearwardly from the front of the end sections and has a lower wall of greater vertical height than the upper wall and offset rearwardly from such upper wall substantially as shown.

I claim:

The ornamental design for a base for machine tools or the like, substantially as shown and described.

ROBERT ELVIN CONOVER.
